CLAIM

The ornamental design for a swimming pool cleaning robot as shown and described.

DESCRIPTION

FIG. 1 is a front, left perspective view of the swimming pool cleaning robot;

FIG. 2 is a bottom, front perspective view thereof;

FIG. 3 is a top, rear perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken lines shown in the drawings depict portions of the swimming pool cleaning robot that form no part of the claimed design.

1 Claim, 9 Drawing Sheets
